Primary Examiner — T Chase Nelson*Assistant Examiner* — Jonathan J. Han(74) Attorney, Agent, or Firm — Pearne & Gordon LLP(57) CLAIM

The ornamental design for a vehicle roof rack, as shown and described.

DESCRIPTION

FIG. 1 is a perspective top view of a vehicle roof rack, showing our new design;

FIG. 2 is a perspective bottom view thereof;

FIG. 3 is a front view thereof, the back view being identical thereto;

FIG. 4 is a left side view thereof, the right side view being identical thereto;

FIG. 5 is a top view thereof; and,

FIG. 6 is a bottom view thereof.

The broken lines in the drawings represent unclaimed subject matter and form no part of the claimed design.
